UNITED STATES PATENT OFFICE.

TERKEL NELSEN, OF HOBOKEN, NEW JERSEY.

DRY-DOCK.

SPECIFICATION forming part of Letters Patent No. 735,569, dated August 4, 1903.

Application filed April 11, 1903. Serial No. 152,239. (No model.)

To all whom it may concern:

Be it known that I, TERKEL NELSEN, a citizen of the United States, residing at Hoboken, in the county of Hudson and State of New Jersey, have invented new and useful Improvements in Dry-Docks, of which the following is a specification.

My invention relates to new and useful improvements in dry-docks, and more especially to mechanism for centering vessels within the same.

The object of the invention is to provide simple and inexpensive mechanism which can be readily applied to docks of ordinary construction and by means of which a vessel may be drawn to the center of the dock prior to the withdrawal of water from the dock.

Another object of the invention is to so construct the mechanism employed as to enable it to be used in connection with vessels of different sizes.

With the above and other objects in view the invention consists in providing a drum adapted to be rotated by suitable mechanism to which are secured cables extending to opposite sides of the dock and having means at the free ends thereof for engaging the opposite sides of the vessels to be supported. Said cables are of such length as to permit the hooks thereof to be brought together only at a point directly above the center of the dock. It is therefore obvious that when the drum is rotated the hooks will be moved in opposite directions at the same speed and will engage the opposite sides of the vessel and move the vessel to the center of the dock.

The invention also consists in the further novel construction and combination of parts hereinafter more fully described and claimed, and illustrated in the accompanying drawing, which is a section through a dock having a vessel secured in position therein and showing in dotted lines the positions of the parts when larger or smaller vessels are supported thereby.

Referring to the drawing by numerals of reference, 1 is the outer sheathing of the dock, upon which are mounted suitable supporting-beams 2 for holding the floor 3 of the dock in proper relation thereto. Brace-beams 4 are arranged in different positions between the floor and the bottom sheathing of the dock

and are also located upon the side of the dock for the purpose of holding the inner side walls 5 thereof in position.

55

An ordinary form of floating dock has been illustrated by me, and it is unnecessary to employ a particular construction when my invention is used. In docks of this character a pump is usually employed for continuously removing the water therefrom, and in the drawing I have shown the shaft 1' of said pump provided with a friction-pulley 2', which is arranged directly above the friction-pulley 3', having a drum 4' thereon. A friction-pulley 5' is interposed between pulleys 2' and 3' and is mounted in sliding bearings, and this pulley is adapted to be moved into or out of operative relation with pulleys 3 by means of a lever 6 or in any other suitable manner. The ends of cables 7 and 8 are secured to the drum 4' and are adapted to be simultaneously wound thereon when the said drum is rotated. One of these cables 7 extends through one side of the dock and is provided at its free end with a suitable hook 9 or any other suitable means whereby it may be rigidly fastened to one side of the vessel. The other cable 8 extends downwardly between the walls and bottoms of the dock and is mounted on suitably-located pulleys 10, swiveled to beams 11, arranged adjacent to the lower ends of the side walls 5, and said cable extends from the upper end of the side of the dock opposite to that upon which drum 4 is located and is provided at its free end with a hook 12 or any other suitable securing means. These cables are of such length that the hooks when drawn toward each other will meet at the center of the dock, and therefore it is obvious that when the cables are wound upon the drum the hooks thereof will be moved from each other simultaneously and will center the vessel within the dock by drawing the same to one side or the other until both cables are taut. Where a vessel of ordinary size is held in position within this dock, it is merely necessary to extend the cables 7 and 8 directly from the sides of the dock to the gunwales of said vessel. When, however, a smaller vessel is to be held in position, the cables can be brought downward under hooks 13 or other suitable holding means, as illustrated in dotted lines in the drawing, and where

boats of unusually large proportions are with-
in the dock it is necessary to extend the ca-
bles over hooks 14 or other securing means
extending from masts 15, suitably connected
5 to the sides of the dock and extending upward
therefrom. Suitable bilge-blocks may be ar-
ranged upon the floor of the dock, as ordi-
narily, for supporting the vessel in proper pos-
ition after the withdrawal of the water from
10 the dock.

In the foregoing description I have shown
the preferred form of my invention; but I do
not limit myself thereto, as I am aware that
15 modifications may be made therein without
departing from the spirit or sacrificing any
of the advantages thereof, and I therefore re-
serve the right to make such changes as fairly
fall within the scope of my invention.

Having thus described the invention, what
20 is claimed as new is—

1. The combination with a dock having a
power-shaft thereon; of a drum adapted to be
rotated by said shaft, cables connected to and
adapted to be simultaneously wound upon the
25 drum, said cables extending to opposite sides
of the dock, and means for securing the ca-
bles to a vessel in the dock.

2. The combination with a dock having a
power-shaft thereon; of a drum, means for
30 transmitting motion from said shaft to the
drum, cables connected to and adapted to be
wound upon the drum simultaneously, said
cables extending to opposite sides of the dock,

and means upon the free ends of the cable
for engaging the opposite sides of a vessel 35
within the dock.

3. The combination with a dock having a
power-shaft thereon; of a drum, a movable
pulley interposed between said shaft and
drum, whereby rotary motion may be im- 40
parted to the drum from the shaft, cables se-
cured to and adapted to be wound upon the
drum simultaneously, one of said cables ex-
tending longitudinally between the walls and
bottoms of the dock to the opposite sides 45
thereof, means upon the free ends of the ca-
bles for engaging the opposite sides of a ves-
sel within the dock, and masts upon the dock
for supporting the cables thereabove.

4. The combination with a dock; of cables 50
extending from opposite sides of the dock and
adapted to be secured to a vessel in the dock,
and means for simultaneously moving the
ends of the cables in opposite directions.

5. The combination with a dock; of cables 55
extending from opposite sides thereof and
adapted to be secured to opposite sides of a
vessel in the dock, and means for simultane-
ously operating the cables for centering the
vessel in the dock. 60

In testimony whereof I affix my signature
in presence of two witnesses.

TERKEL NELSEN.
